UNITED STATES PATENT OFFICE.

ALBERT KERR, OF ANNAPOLIS, MARYLAND.

COMBINED CURTAIN-POLE AND SHADE-ROLLER BRACKET.

SPECIFICATION forming part of Letters Patent No. 758,759, dated May 3, 1904.

Application filed January 25, 1904. Serial No. 190,586. (No model.)

To all whom it may concern:

Be it known that I, ALBERT KERR, a citizen of the United States, residing at Annapolis, in the county of Anne Arundel and State of Maryland, have invented certain new and useful Improvements in a Combined Curtain-Pole and Shade-Roller Bracket, of which the following is a specification.

My invention relates to certain new and useful improvements in combined curtain-pole and shade-roller brackets, and has for its primary object the provision of novel construction for supporting the curtain-pole at a point above the shade-roller-supporting means.

I form my improvement by stamping a single blank from a suitable sheet of metal and then bend the same into its proper shape. This is a very material feature, as I overcome the item of waste material and further produce a very simple device which can be manufactured at a small expense.

My invention further consists in the minor details of construction and arrangements of parts hereinafter referred to, and specifically, 5 pointed out in the appended claims.

In the accompanying drawings, in which like numerals of reference indicate like parts throughout the several views, Figure 1 is a diagrammatical view of my improvement in its operative position, the curtain-pole and shade-roller being shown in dotted lines, while the brackets are shown in full lines. Fig. 2 is a view in side elevation of one of the brackets. Fig. 3 is a plan view of the blank from which 5 one of the brackets is formed. Fig. 4 is a view in front elevation of the completed bracket.

The blanks from which the brackets are formed are both substantially the same, the only difference lying in the formation of the bearings for the shade-roller, the one being circular, as shown in Fig. 1, and the other approximately rectangular, as shown in the same figure or more clearly in Figs. 2 and 3. It will therefore be obvious that a description 5 of one will suffice.

1 indicates a body portion at the rear edge of which is provided an inturned flange 2, extending at right angles to said body portion and being formed with openings 3 for the re-

ception of screws or other suitable means for securing the same in position. The body portion is further provided at its upper edge with an approximately semicircular seat 4, the edges of which are struck upwardly, as at 5, to 55 form flanges on which the curtain-pole rests. At a point adjacent the lower forward edge of the body portion I form arms or ears 6, in which the opposite ends of the curtain-roller are journaled.

Thus far I have described brackets of such construction which will permit of their accommodation on opposite side members of a window-casing. I have found, however, in practice that it is often very desirable to so 60 position these brackets that the same will not project without the window-frame, and to this end I form the body portions thereof with apertures 7, through which the securing means can be passed in lieu of the openings 3.

In the manufacture of the brackets I preferably stamp blanks of suitable contour, as shown in Fig. 3 of the drawings, then bend the same on the line α to form the rear edge flanges 2, and finally bend the tongues 5^a outwardly to 75 form flange 5, heretofore described. The openings can be formed simultaneously with the stamping operation, and it will thus be apparent that when the two operations of bending the parts referred to subsequently to 80 the stamping of the blank that the article will be finished and in condition to be placed upon the market.

While I have described my improvement as being more particularly adapted for use in connection with curtain-poles and shade-rollers, yet I wish it understood that it can also be advantageously employed for supporting portières and the like.

In the foregoing I have described a construction capable of performing the various functions assigned to it; but I desire the right to make such alterations or changes in the minor details of constructions as fall within the scope of the annexed claims.

Having thus fully described my invention, I claim as new and desire to secure by Letters Patent—

1. A device of the type set forth formed from a single blank and comprising a body portion 100

provided at its rear edge with a flange and having its upper edge out away to form a seat, and a flange bent outwardly from the edges of said seat, substantially as and for the purposes 5 specified.

2. A bracket comprising a body portion formed in its upper edge with an approximately semicircular seat, a flange projecting from the edge of said seat, an ear carried by 10 said body portion, said ear being apertured and disposed beneath said seat, a flange formed

integral with the rear edge of said body portion and being apertured, said body portion being formed with apertures, the whole being formed from a single blank.

In testimony whereof I have signed my name to this specification in presence of two witnesses.

ALBERT KERR.
